UNITED STATES PATENT OFFICE.

ROBERT O'NEILL, OF LEADVILLE, COLORADO.

FEED-WATER HEATER.

SPECIFICATION forming part of Letters Patent No. 327,553, dated October 6, 1885.

Application filed February 9, 1885. Serial No. 155,295. (No model.)

To all whom it may concern:

Be it known that I, ROBERT O'NEILL, of Leadville, in the county of Lake and State of Colorado, have invented a new and useful Improvement in Boiler Feed-Water Heaters; and I do hereby declare that the following is a full, clear, and exact description of the same, reference being made to the accompanying drawings, forming a part of this specification.

My object in this invention is to provide an apparatus for heating and filtering feed-water for steam-boilers; and it consists in the features of improvement hereinafter described. I attain these objects by the mechanism illustrated in the accompanying drawings, in which similar letters refer to similar parts throughout the several views.

Figure 1 is a vertical section of Fig. 3 on the line *x x*. Fig. 3 is a top view of Fig. 1 with the cover removed. Fig. 2 is a sectional view of the regulating-float *a*, Fig. 1.

A represents the casing or shell, which is divided into two compartments, (marked *B* *C*.) from the latter of which, *C*, the water is taken for the supply of the boiler. The plate *b*, whose edge is turned downward or at right angles with the top or face, is provided with holes, through which the rivets *30* are passed which secure it to the shell *A*. It is also provided with a number of tubes, *c*, thirty inches in length, (more or less,) through which the water passes in descending from *B* to *C*. These tubes are about three-fourths *35* of an inch in diameter, and the plate *b* is provided with a sufficient number to enable the exhaust-steam which enters through the opening *D'* and passes up through the pipes *c* to come in contact with thin sheets of water *40* only, which is heated by absorption from the exhaust-steam, which is thereby condensed, the water returning down the tube *c* to the tank or compartment *C*, through which it is conveyed through the opening *D* to the boiler.

The water required to be heated, besides the amount obtained by condensing the steam, is supplied by the circular pipe *d*, Figs. 1 and 3, which has perforations. (Shown by the dots *e* on *d*, Fig. 1.) Through these per-

forations or holes the water enters the case *50* or shell *A*, forming a thin spray, which, being cold, condenses any remaining steam that may escape through the top of the pipes *c*. The amount of water which passes in this way into the case or shell *A* is regulated automatically by the water *f* in compartment *C*, which, as its surface is raised by the addition of water from condensed steam or from the pipe *d*, also raises the water in *a*, which causes the float-ball *g* to rise. The *60* float ball *g* is provided with a rod, *a'*, whose other and upper end is attached to a valve, *b'*, which is set so that the raising of the float-ball *g*, which also raises the rod *a'*, which in turn by its connection shuts off the *65* water which passes from a supply-tank through the pipe *c'* and valve *b'* into the circular pipe *d*, and through the perforations in *d* into the case or shell *A* and compartment *B*. The water is turned on by the same means *70* working in the opposite direction, caused by lowering the water *f* in the compartment *C*, which, being connected with the float-case *a* by the pipe *d'*, also lowers the water in *a'*, which operates the valve *b'* in the manner *75* described, which arrangement keeps the water *f* in compartment *C* at about the same height at all times. At this height a suitable faucet, *f'*, is placed in the shell for the purpose of drawing off from the surface of the *80* water *f* the oil and dirty matter which will come from the engine and float on the surface. In the shell or case are hand-holes *85* (marked *g'*) for the purpose of facilitating in cleansing out sediment. The water contained in compartment *B* is hot at the top, the cold being at the bottom from natural causes. Therefore as the cold water enters from the pipe *d*, it at once goes to the bottom, and as it is heated goes to the top, and, when near the *90* upper end of the pipe *c*, it reaches such a degree of heat that the dirt, lime, and other materials contained in solution are precipitated and fall to the bottom of compartment *B*, where they remain until removed through *g'*. *95*

I am aware that prior to this invention heaters have been made with pipes set in plates through which the exhaust-steam passes, as

in Patent No. 149,148, issued March 31, 1874. I therefore do not claim that combination, broadly; but

What I do claim, and desire to secure by 5 Letters Patent, is—

1. In a feed-water heater, the shell A, divided into two compartments by a plate, b, the upper one containing pipes c, in combination with the float-case a, substantially as and for 10 the purpose set forth.

2. The combination of a shell or case, A, provided with outlet D and inlet D', float-case a attached thereto, float-ball g, rod a', valve b', and circular spray-pipe d.

ROBERT O'NEILL.
